RADIO CONTACT PIN

Waldemar H. von Scheven, Waterbury, Conn.

Application August 12, 1933, Serial No. 684,921

1 Claim. (Cl. 173—361)

This invention relates to certain new and useful improvements in radio contact pins.

The object of this invention is to provide a contact pin of the type forming a part of lamps, 5 radio tubes, attachment plugs and the like and to provide a pin constructed in a manner to eliminate injury to the base member with which the same is connected during the attachment of the pin to the base member.

- 10 In contact pins of this general character, it is customary to provide the pin with an annular bead portion intermediate its end to constitute an abutment for engagement with the outer face of the base member of a lamp or the like, but it 15 has been found in pins of such a structure that the same have a tendency to bend in the vicinity of the annular bead during attachment of the pin to the base member resulting in having the opposite end section out of alignment.
- 20 It is therefore a further object of this invention to produce a radio contact pin which remains in true alignment throughout its length during the mounting thereof in the base member and also in service, the pin being formed of sheet metal 25 and rolled into tubular form with a pair of diametrically opposite ears struck out therefrom in lieu of the usual annular bead, this arrangement effecting a saving of material in the manufacture of the pin and also providing for intimate 30 contact between the pin and base member to prevent turning of the pin during the heading or riveting operation.

With the above and other objects in view that will become apparent as the nature of the invention is better understood, the same consists in the novel form, combination and arrangement of parts hereinafter more fully described, shown in the accompanying drawing and claimed.

In the drawing:—

- 40 Figure 1 is a developed plan view of the blank from which the radio contact pin is made;
- Figure 2 is a plan view similar to Figure 1, showing ears struck out from intermediate portions of the blank adjacent one end thereof;
- 45 Figure 3 is a side elevational view of the blank partly folded into tubular formation showing the diametrically opposite struck out ears;
- Figure 4 is a side elevational view of the blank completely rolled into tubular formation;
- 50 Figure 5 is a top plan view of the partially folded blank shown in Figure 3;

Figure 6 is a top plan view of the completely folded blank shown in Figure 4;

Figure 7 is another side elevational view of the completely formed contact pin;

Figure 8 is a side elevational view of the contact pin anchored to a base member that is fragmentarily illustrated in section;

Figure 9 is a top plan view of the contact pin as shown in Figure 7; and

Figure 10 is a top plan view of the contact pin as shown in Figure 8 detached from the base member.

As shown in Figures 1 and 2, the radio contact pin is formed from a sheet metal blank 15 of rectangular form in developed plan view as illustrated and has parallel side edges 16 and toothed or serrated end edges 17 and 18 respectively. The blank 15 as shown in Figure 1 is provided with a pair of U-shaped slits 19 at one side of the transverse median line of the blank adjacent the serrated end 17 with the curved sides of the slits directed toward said end 17 and the material of the blank bounded by said slits 19 is struck out to provide a pair of transversely aligned 10 ears 20 as shown in Figure 2.

In folding or rolling the blank 15 into cylindrical formation to produce the contact pin, the same is first rolled into U-shape as shown in Figures 3 and 5 with the ears 20 diametrically opposite each other. The side edges 16 of the blank 15 are then folded or rolled inwardly as shown at 16a in Figures 4 and 6 to produce the cylindrical contact pin 15a, the ears 20 remaining diametrically positioned with respect to the cylindrical pin 15a. The serrated ends 17 and 18 of the pin are then rolled inwardly as at 17a and 18a respectively to provide restricted openings for the passage of conductor wires.

In mounting the contact pin in a lamp base, radio tube or the like, the base member 21 of the tube 22 is first provided with a cylindrical opening 23 through which the end portion 17 of the pin is inserted from the outer side of the base member, the pin end being moved through the opening 23 until the diametrically opposite ears 20 move into frictional engagement with the outer face of the base member 21. The serrated end 17 of the pin is then headed over or riveted as at 17b for cooperation with the ears 20 in forming locking means for retaining the contact pin rigidly connected with the base member 21 of the lamp device. The headed or riveted end of the contact pin is clearly illustrated in Figures 8 and 10.

A considerable saving of material in the manufacture of the contact pin is noted by the use of the struck out ears 20 in lieu of the usual annular bead, the ears 20 acting to lock the pin to the base member against rotary movement.

in the opening 23 during the heading or riveting operation on the end 17 of the pin.

From the above detailed description of the invention, it is believed that the construction and use thereof will at once be apparent and while there is herein shown and described the preferred embodiment of the invention, it is nevertheless to be understood that minor changes may be made therein without departing from the spirit and scope of the invention as claimed.

0 I claim:—

5 An electric fitting having an insulating base

and an associated rigid tubular contact pin, said pin being formed from sheet metal and having diametrically opposite ears struck-out therefrom adjacent one end for engagement with the outer face of the base, the openings formed by the struck-out ears being located within the base opening through which the pin extends and said end of the pin being serrated to provide fingers directed outwardly at right angles to cooperate with the ears for securing the pin in the base. 10
